(57) **CLAIM**

The ornamental design for a carbine firearm, as shown.

DESCRIPTION

FIG. 1 is a side view (right-hand side) of the carbine firearm with the short barrel showing the new design;
FIG. 2 is a side view (left-hand side) thereof showing the new design;
FIG. 3 is a view thereof in perspective at an angle from the bottom and left-hand side;
FIG. 4 is a rear view thereof;
FIG. 5 is a top view thereof;
FIG. 6 is a bottom view thereof;
FIG. 7 is a front view thereof;
FIG. 8 is a detailed view of the buttstock thereof;
FIG. 9 is a detailed view of the magazine thereof;
FIG. 10 is a detailed view of the barrel thereof;
FIG. 11 is a detailed view of the forestock thereof;
FIG. 12 is a detailed view of the buttstock thereof in perspective;
FIG. 13 is a detailed view of the magazine thereof in perspective;
FIG. 14 is a detailed view of the barrel thereof in perspective;
FIG. 15 is a detailed view of the forestock thereof in perspective;
FIG. 16 is a side view (right-hand side) of the carbine firearm with the long barrel showing the new design;
FIG. 17 is a side view (left-hand side) thereof showing the new design;
FIG. 18 is a view thereof in perspective at an angle from the bottom and left-hand side;
FIG. 19 is a rear view thereof;
FIG. 20 is a top view thereof;
FIG. 21 is a bottom view thereof;
FIG. 22 is a front view thereof;
FIG. 23 is a detailed view of the buttstock thereof;
FIG. 24 is a detailed view of the magazine thereof;
FIG. 25 is a detailed view of the barrel thereof;
FIG. 26 is a detailed view of the forestock thereof;
FIG. 27 is a detailed view of the buttstock thereof in perspective;
FIG. 28 is a detailed view of the magazine thereof in perspective;
FIG. 29 is a detailed view of the barrel thereof in perspective; and,
FIG. 30 is a detailed view of the forestock thereof in perspective.
